Primary Examiner—T. Chase Nelson*Assistant Examiner*—David G Muller(74) *Attorney, Agent, or Firm*—Finnegan, Henderson, Farabow, Garrett & Dunner, LLP(57) **CLAIM**

The ornamental design for a tissue excision device, as shown and described.

DESCRIPTION

FIG. 1 is a perspective view of the tissue excision device of the present invention showing the new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view.
